CLAIM

The ornamental design for a bag, as shown and described.

DESCRIPTION

FIG. 1 is a top, front, right perspective view of a bag showing our new design;

FIG. 2 is a front view thereof;

FIG. 3 is a rear view thereof;

FIG. 4 is a right side view thereof;

FIG. 5 is a left side view thereof; and,

FIG. 6 is a top view thereof.

The broken lines between shaded and unshaded areas depict the bounds of the claim and form no part thereof. The zipper outline is claimed with a solid line while the unshaded subject matter surrounding the outline forms no part of the claim. The logo patch shown in broken lines depicts a portion of the article and forms no part of the claim. The broken lines crossing claimed, shaded surfaces depict a seam and stitching and form no part of the claim.

1 Claim, 5 Drawing Sheets
